TWO DIMENSIONAL SWEEP CIRCUIT

Bagdasar Deradoorian, Detroit, Mich., assignor to The Bendix Corporation, a corporation of Delaware
Filed Dec. 14, 1959, Ser. No. 859,472
11 Claims. (Cl. 315—23)

This invention pertains to a two dimensional sweep circuit and, more particularly, to a simplified sweep circuit usable in a thin television tube and the like.

It is an object of this invention to provide a two dimensional sweep circuit for causing an electron beam to be swept periodically across a given area, such as a phosphor screen in a television tube, with the circuit assembly having a very thin depth and requiring a minimum number of electrical connections and circuit components.

It is an object of this invention to provide a two dimensional sweep circuit wherein an electron stream is moved along one dimension of and parallel to a resistive plate which has a variable voltage applied across a second dimension of the plate to cause the moving electron stream to be repelled in a direction normal to the plate at various points depending on the value of the varying voltage.

It is another object of this invention to provide a television tube wherein a stream of electrons from an electron gun is directed along a resistive strip which has a variable potential placed thereacross with the stream being repelled in a direction normal to the strip at various points along the strip as the potential is varied, with the repelled electron stream being moved along one dimension of and parallel to a resistive plate having a variable voltage placed across the second dimension of the plate so that the electron stream is repelled at various points along the second dimension of the plate as the voltage is varied, and with a phosphor screen being placed parallel and adjacent to the resistive plate to receive the repelled electron stream.

These and other objects will become more apparent when a preferred embodiment of this invention is considered in connection with the drawings in which:

FIGURE 1 is an elevational view, partly broken away, of the schematic diagram of a preferred embodiment of this invention;

FIGURE 2 is an end view of the embodiment shown in FIGURE 1;

FIGURE 3 is a graphical illustration of the manner in which voltage is varied along a resistive length; and

FIGURE 4 is a schematic diagram of a second embodiment of this invention.

It has been an object for a number of years of the electronics industry and especially the television development and manufacturing industries, to provide a thin two dimensional sweep tube. Tubes of this nature have been developed but, due to their complexity and other difficulties, are not in common use. This invention provides a relatively simple tube construction of very narrow dimensions which can provide the sweep necessary along a phosphor screen of a television tube. This is done with only two electrical connections to a vertical deflection plate which is manufactured of a resistive material so that a potential drop is developed thereacross when a voltage is applied thereto. An electron stream, such as emanates from an electron gun in a television tube, is caused to move along the plate, and by varying the voltage across the plate the stream is repelled in a direction perpendicular from the plate along the dimension across which the voltage is applied.

In FIGURE 1 is an electron gun 20 emitting a stream of electrons 21 which vary in intensity according to picture information received from a television transmitting station by a receiver 19. The stream 21 is directed along a strip 22 which may be of glass or Bakelite and which

2

has a resistive coating 23 of predetermined ohmage on one surface thereof. A coating of this nature may be obtained by spraying an antimony and tin solution on the glass surface in proportions and thickness corresponding to the desired resistance. Between ends 24 and 25 of strip 23 is placed a variable voltage in the form of a sawtooth pulse 26 produced by source 28.

The stream 21 is repelled in a direction normal from the strip 22 when any point of the strip reaches a voltage E_r (FIGURE 3). By applying the sawtooth pulse 26 at end 25, the potential at end 25 is gradually decreased due to the decreasing slope of the sawtooth pulse. When the voltage at end 25 of strip 22 is equal to E_r , the electron stream will be repelled from the strip at point 25; as the voltage at end 25 decreases, the stream 21 will be repelled at earlier points along the strip. This is so since, when the voltage at end 25 is decreased to E_1 , the point at which the stream 21 will be repelled from strip 22 will be P_1 , that point where the potential gradient line of voltage E_1 crosses the E_r line. As the voltage is further decreased to E_2 , the electron stream 21 will be diverted at point P_2 of strip 22 since it is at this point that the potential gradient line for voltage E_2 crosses the repelling voltage line of E_r . In this manner the electron stream 21 is repelled from strip 22 with the point of repelling moving in a right-to-left direction with a rate depending on the slope of pulse 26.

Placed in perpendicular relation to horizontal strip 22 is a vertical plate 30 which also may be of glass, Bakelite, or a similar insulative material coated with a resistive material 31 of predetermined ohmage and which receives a pulse 34 from source 29 which is connected at the top 32 and bottom 33 of the plate 30 so that a potential drop is formed along the vertical dimension of plate 30. The pulses 26 are much more frequent than the pulses 34 and when applied to the plate 30 each pulse causes the electron stream 21 (FIGURE 2) to be repelled from the plate 30 at points along the plate which move from top to bottom in much the similar manner that the stream is repelled at various points from strip 22.

Parallel to and spaced adjacent to plate 30 is a phosphor screen 40 which receives the repelled electrons from plate 30. Screen 40 has a coating of a material which will radiate visible light when activated by the electron stream in proportion to the intensity of the electron stream. Due to the pulses applied to strip 22 and plate 30, the stream 21 is caused to scan the screen 40 and if picture information is applied to stream 21, a corresponding picture will be formed on the screen 40. It would, of course, be necessary to synchronize the pulses 26 and 34 with corresponding pulses in the transmitting unit.

Briefly, the operation of this embodiment is as follows: An electron stream 21 is emitted from gun 20 which may be modulated in accordance with picture or other information. The stream is directed along strip 22 which has a resistive coating 23 along the surface thereof and which has connected at ends 24 and 25 a variable voltage source in the form of a negative sawtooth pulse. The pulse is applied to end 25 of the strip and as end 25 becomes increasingly negative, electron stream 21 will be repelled from the strip at points increasingly distant from end 25. This is so because a potential gradient is formed along strip 22 due to current flow in the resistive coating. In this manner the stream 21 moves from the right side of plate 30 to the left side, once for every sawtooth pulse.

While the stream is moving across plate 30, a series of negative sawtooth pulses is applied between the top edge 32 of plate 30 and the bottom edge 33. For every negative sawtooth pulse that is applied between edges 32, 33 the electron stream is repelled along a line from the top edge to the bottom edge of the plate 30 and impinges upon a phosphor screen 40. The pulses applied to the

strip 22 are frequent enough so that the picture formed on screen 40 appears continuous to the human eye.

With this embodiment only two electrical connections are necessary to plate 30 and strip 22 with corresponding reduction in circuit components and complexities.

Other means may be utilized to cause stream 21 to move along the horizontal dimension of plate 30. These means could include a pair of deflection plates between which the stream passes and to which a variable voltage is applied to influence the stream through an arcuate path as illustrated in FIGURE 4. In FIGURE 4 a sawtooth voltage pulse is applied by source 45 between plates 42, 44 which are placed adjacent the mouth of an electron gun 47, energized by receiver circuit 46 which is similar to receiver circuit 19 in FIGURE 1, and influence the electron stream 48 in an arcuate path to move across plate 30A which is pulsed in the same manner as plate 30 in the previous embodiment to repel the electron stream into a phosphor stream. Voltage source 28a provides a sawtooth voltage across plate 30a which is similar to the voltage placed across plate 30 in FIGURE 1.

Although this invention has been disclosed and illustrated with reference to particular applications, the principles involved are susceptible of numerous other applications which will be apparent to persons skilled in the art. The invention is, therefore, to be limited only as indicated by the scope of the appended claims.

Having thus described my invention, I claim:

1. Television tube sweep circuit comprising an electron gun for emitting a modulated electron stream in a first direction, a strip having a coating of resistive material of predetermined ohmage, said stream being directed along said strip, means for applying a sawtooth voltage across said resistive coating causing a corresponding current to flow therethrough and progressively lower the potential along said coating to progressively repel said stream in a second direction from said coating in a plane substantially perpendicular to said coating, a plate having a resistive coating of predetermined ohmage being placed in a plane adjacent and substantially parallel to the plane of said stream, means for applying a sawtooth voltage across said plate in a direction substantially parallel to the said second direction of said stream to progressively repel the stream from said plate coating, a phosphor screen being placed in a plane adjacent and substantially parallel to said plate and being located substantially in front of said resistive coating in order to receive said repelled stream.

2. Two dimensional sweep means comprising means for emitting a charged particle stream, a plate means having a resistive surface, means for causing said stream to move across at least a portion of said plate means, variable voltage means being placed along a portion of the resistive surface of said plate means thereby causing a corresponding current flow in said resistive surface of said plate means providing a predetermined potential drop and voltage gradient across said resistive surface, so that the stream moving across said resistive surface is deflected in a direction having a normal component to said plate means, said stream being deflected at points along said resistive surface which vary in a manner corresponding to manner in which the voltage varies across said resistive surface.

3. The apparatus of claim 2 with the means for causing said stream to move across at least a portion of said plate means comprising, a second plate means having a resistive surface, said second plate means being placed adjacent to edge of said first mentioned plate means, variable voltage means being placed along a portion of said resistive surface of said second plate means, thereby causing a corresponding current flow in said

5 resistive surface of said second plate means, providing a predetermined voltage drop and voltage gradient across said resistive surface of said second plate means,

10 so that the stream moving across said resistive surface is deflected in a direction having a normal component to said second plate means and in a direction which causes said stream to move across and have a substantial component parallel to said first mentioned plate means, said stream being deflected at points along said resistive surface of said second plate means which vary in a manner corresponding to the manner in which the voltage varies across the resistive surface of said second plate means.

15 4. The apparatus of claim 3 with means to cycle the voltage placed across the resistive surface of said first mentioned plate means in a predetermined ratio to the number of times the voltage placed across the resistive surface of said second plate means is cycled.

20 5. The apparatus of claim 4 with a phosphor screen being placed adjacent and parallel to said first mentioned plate means, said charged particle stream being directed between said phosphor screen and said first mentioned plate means,

25 said charged particle stream being repelled from said first mentioned plate means towards said phosphor screen to impinge upon said phosphor screen.

6. The apparatus of claim 5 with said charged particle stream emitting means being an electron gun for modulating the intensity of said stream according to received information.

30 7. The two dimensional sweep means of claim 2 where said means for causing said stream to move along a portion of said plate means comprises an electrode located on each side of said electron stream, means to apply voltages to said electrodes to cause said stream to reciprocate between said electrodes in a plane substantially parallel to said plate means.

35 8. Television tube sweep circuit comprising an electron gun for emitting a modulated electron stream, an electrode being placed on each side of said stream, voltage means being connected to said electrodes to cause said stream to reciprocate in a plane having a substantial component parallel to said electrodes, a plate having a resistive coating of predetermined ohmage being placed in a plane adjacent and substantially parallel to said plane of said stream reciprocation, means for applying a sawtooth voltage across said plate in a direction having a substantial component parallel to a line perpendicular to a line connecting said electrodes to progressively repel the stream from said plate coating, a phosphor screen being placed in a plane adjacent and substantially parallel to said plate and being located substantially in front of said resistive coating in order to receive said repelled stream.

40 9. Two dimensional sweep means comprising means for emitting a charged particle stream, a resistive material being of a continuous structure over the area to be traversed by the charged particle stream, means for causing said stream to move in a direction having a substantial component which is parallel to the face of said continuous resistive material, said stream being substantially parallel to a given line on said resistive material as it moves across said resistive material, cyclic voltage means being connected to said resistive material at two contact points which are on a line which has a substantial component parallel to said given line on said resistive material, said cyclic voltage means causing a changing voltage gradient corresponding to each voltage cycle so that said stream in moving across said resistive material is repelled from said resistive material at various points along the stream path corresponding to said voltage gradient.

10. The two dimensional sweep means of claim 9 wherein said means for causing said stream to move substantially parallel to the face of said resistive material comprises a continuous resistive strip of predetermined ohmage placed adjacent to an edge of said resistive material, said strip being substantially perpendicular to a line passing through said contact points of said cyclic voltage means, voltage means for applying a cyclic voltage across the length of said strip being connected to the ends of said strip, said charged particle stream being directed by said emitting means in a direction having a substantial component parallel to said strip adjacent to said resistive material, said stream being repelled from said strip at succeeding points along said strip depending upon the voltage gradient determined by the cyclic voltage applied to said strip. 15

11. The two dimensional sweep means of claim 9 where said voltage means provides a plurality of voltage cycles each time said stream moves adjacent to and across the face of said resistive material, so that said stream is repelled at a predetermined number of points from said resistive material.
